(57) **CLAIM**

The ornamental design for a chandelier, as shown and described.

DESCRIPTION

FIG. 1 is a bottom plan view of a chandelier showing my new design;

FIG. 2 is a top plan view thereof;

FIG. 3 is a front elevational view thereof;

FIG. 4 is a left side elevational view thereof; and,

FIG. 5 is a perspective view thereof.

The broken lines shown on the drawings depict portions of the chandelier that form no part of the claimed design.
